E. F. DELERY.
AXIAL FLOW PUMP AND TURBINE.
APPLICATION FILED NOV. 10, 1913.

1,150,747.

Patented Aug. 17, 1915.

UNITED STATES PATENT OFFICE.

EUGENE FRANK DELÉRY, OF NEW ORLEANS, LOUISIANA.

AXIAL-FLOW PUMP AND TURBINE.

1,150,747.

Specification of Letters Patent. Patented Aug. 17, 1915.

Application filed November 10, 1913. Serial No. 800,116.

To all whom it may concern:

Be it known that I, EUGENE FRANK DELÉRY, a citizen of the United States, residing at New Orleans, in the parish of Orleans and State of Louisiana, have invented new and useful Improvements in Axial-Flow Pumps and Turbines, of which the following is a specification.

My invention relates to improvements in axial flow pumps and turbines and consists in means of guiding the flow of liquid from the suction opening of the pump or turbine to the wheel or runner thereof and thence to the discharge opening of the pump or turbine with the least possible agitation or change of velocity of the liquid, at the same time making use of the shortest possible shaft with a consequent reduction of vibration in the runner, shaft, and bearings. I attain these objects by means of the mechanisms illustrated in the accompanying drawings in which—

Figure 1 is a half section and half elevation of a double unit (or two units) of a pump or turbine connected to a common suction pipe at 10 by the suction volutes 1, which discharge through the runner or runners 2 to the discharge volutes 3 and thence to the discharge pipe or pipes, in the case of a pump. Fig. 2 is a three quarter elevation and quarter section of a single pump or turbine showing entrance volute 1, balanced runner 2, diffusion vanes and diffusion vane chamber 4 and discharge volute 3, in the case of a pump. Fig. 3 is a plan view of one form of runner to be used in connection with this form of pump or turbine. Figs. 4, 5, 6, and 7 are elevations of different runners with shroud rings broken away in order to show the characteristic forms of the blades which may be used with this type of pump or turbine.

Similar numerals refer to similar parts in all figures and the word runner is to be interpreted to mean the wheel or rotor of the pump or turbine and the word volute to mean a spirally formed tubular fluid passage, not necessarily the volute of a circle.

The following is a list of the numerals 50 and the parts to which they refer.

1 is a suction volute in the case of a pump or the discharge volute in the case of a turbine other than an outward flow radial discharge turbine.

2 is the runner in the case of either pump or turbine.

3 is the discharge volute in the case of a pump or the suction volute in the case of a turbine.

4 is a diffusion vane chamber, with its 60 vanes, which may be used when so desired but which forms no part of this invention.

5 indicates the bearings.

6 indicates the stuffing boxes.

7 is the shaft.

8 is the balancing chamber, also not part of this invention.

10 is the suction pipe connection to a pump or the discharge pipe connection to an axial flow turbine.

The method of operation in the case of a pump is as follows: The fluid is admitted from the suction pipe at 10 to the suction volute or volutes 1, each of which is so shaped that it wraps around the shaft in a 75 tubular spiral path and has an annular opening, on the side next the runner, of constant width to the runner two (2), and a constantly decreasing cross sectional area in a spiral direction around the shaft, said 80 sections being taken on planes at right angles to the plane of revolution and radially spaced around the origin of the spiral, the form of these sections to be such as to place the centers of areas in such a position 85 as to leave space at the center of the spiral for stuffing boxes, bearings, and shaft.

I intend wherever I see fit to omit the use of the suction volute but intend to always use the discharge volute but reserve the right 90 to use either only the discharge volute or both the suction and discharge volutes. From volute 1 the fluid is discharged through the runner 2 to either the diffusion blade chamber 4, Fig. 2, or directly to the discharge volute 3 as in Fig. 1, thence to the discharge pipe.

The method of operation in the case of an axial flow runner is well known and not new, I will, therefore, only state that I intend to use this pump or turbine, as the case may be, with either a blade of curved cross section as shown in Figs. 4, 5, 6, or with a blade which has a screw form as in Fig. 7, preference being given to a blade of curved 100 cross section and so formed that its advancing edge is approximately a straight line and in which the curvature of its cross sections taken at right angles to the radii and on different arcs of revolution constantly 105 diminish with their distance from the center of revolution and when projected on a plane 110

- at right angles to the radius and parallel to the axis of the shaft will give sections approximately as shown in Figs. 5 and 6, in which the angles of curvature are more
- 5 nearly parallel to the axis of the shaft near the center of revolution and tend to curve at right angles to the axis of the shaft as the distance therefrom increases. These forms of blades are not new, neither is the
- 10 form of runner nor is the use of diffusion blades in pumps and turbines new and I therefore do not claim these things in themselves but I do claim their use in connection with this form of pump or turbine.
- 15 When used as a turbine the mode of operation is the opposite of the method just described, that is; the fluid would enter at 3 pass through 4 and 2, or only 2, thence to the discharge.
- 20 I claim:
1. An axial flow pump or turbine comprising a rotor chamber having suction and discharge volutes gradually decreasing cross sectionally and designed to impart to fluid
- 25 passing therethrough a rotary motion of

constant velocity, and registering with the rotor chamber by means of an annular opening of constant width in the side of the volutes next to the rotor chamber and forming a part thereof and adapted to impart to 30 the fluid an axial component of flow.

2. In an axial flow pump or turbine, comprising a casing having a cylindrical rotor chamber, a shaft journaled in suitable bearings and a rotor upon the shaft within said chamber, said casing being provided with suction and discharge volutes which are gradually decreasing cross sectionally and designed to impart to the fluid passing therethrough a rotary motion of constant velocity and registering with the rotor chamber by means of an annular opening of constant width in the side of the volute next to the rotor chamber and forming a part thereof and adapted to impart to the fluid an axial 40 component of flow.

EUGENE FRANK DELERY.
